Des. 216,207
Patented Dec. 2, 1969

216,207

PORTABLE DRAFTING DEVICE

Walter C. Tripp and Warren W. Tripp, both of
400 Sunshine Lane, Reno, Nev. 89502

Filed Aug. 29, 1968, Ser. No. 13,321

Term of patent 14 years

Int. Cl. D6—01

U.S. Cl. D33—14

FIG. 2

FIG. 3

FIG. 4

FIG-5

FIG-6

FIG-7

FIGURE 1 is a perspective view of a portable drafting device showing our new design;

FIGURE 2 is a top plan view;

FIGURE 3 is a front elevational view;

FIGURE 4 is an elevational view of one end with the pivotable supporting leg in folded position, the opposite end being substantially a mirror image thereof;

FIGURE 5 is a bottom plan view;

FIGURE 6 is a rear elevational view; and,

FIGURE 7 is a sectional view, the plane of the section being indicated by the line 7-7 in FIGURE 2.

We claim:

The ornamental design for a portable drafting device, as shown and described.
